Attnys.

UNITED STATES PATENT OFFICE

2,001,056

BRACELET CLASP

Charles A. Domler, Providence, R. I., assignor to
The Hadley Company, Inc., Providence, R. I.,
a corporation of Rhode Island

Application November 26, 1934, Serial No. 754,703

7 Claims. (Cl. 24—71)

This invention relates to clasps or fasteners for detachably connecting the ends of cords, straps, ribbons, bands and the like, which will be generically termed strands, and as illustrative 5 of its utility, the invention is herein shown in connection with a watch bracelet of the type in which the strands are suitable for attachment to the opposite ends or sides of a wrist watch.

The principal objects of the invention are to 10 provide a clasp in which the end or ends of a cord, strap or other strand may be easily inserted, securely fastened, and substantially enclosed, even though they are considerably frayed; to provide a clasp which is of simple design, having but few 15 parts, which is of strong and durable construction, and which is economical to manufacture and reliable in operation; and to provide a clasp which is compact, convenient to operate and of pleasing and attractive appearance.

20 Further objects relate to various features of construction and will be apparent from a consideration of the following description and accompanying drawing, wherein:

Fig. 1 is a rear view of a part of a watch bracelet embodying a clasp constructed in accordance with the present invention;

Fig. 2 is a side elevation of the bracelet parts shown in Fig. 1;

Fig. 3 is a longitudinal section through my 30 improved clasp, showing the parts in locking position;

Fig. 4 is an enlarged section substantially on the line 4—4 of Fig. 3;

Fig. 5 is a side elevation of the clasp with its 35 link and lever members in open position;

Fig. 6 is a perspective view of the clasp with the link and lever members in open position;

Fig. 7 is an enlarged end elevation of the clasp 40 with its link and lever members in open position;

Fig. 8 is a side elevation of the clasp with the link member in open position and the lever in closed position; and

Fig. 9 is an enlarged end elevation with the 45 parts as shown in Fig. 8.

The watch bracelet herein shown for the purpose of illustration comprises a looped cord 1 whose ends are secured by means of my improved clasp 2 to an adjustable connector 3 which may be of the type shown in Patent No. 1,966,063 granted to me July 10, 1934, or any other desired form of bracelet connector. The clasp 2 comprises a sheet metal holder or casing member which is preferably substantially rectangular in shape having a continuous top wall 5 and side walls 6 and 7 collectively defining a chamber 9 having an open bottom and open ends. One end of the clasp is secured to the connector 3 in any suitable manner as, for example, by means of a pintle 10 which passes through a socket member carried by the connector 3.

A link member 12 (Fig. 5) is pivotally connected to the holder adjacent to its free end and is freely movable from a closed or nested position within the chamber 9, as shown in Figs. 3 and 4, to an open or extended position as shown in Figs. 5 to 9. The link member 12 preferably consists of a U-shaped element having parallel legs 14 and 15 pivotally attached at their free ends to the side walls 6 and 7, respectively, by means of pins 16 and 17. The legs 14 and 15 10 constitute a pair of spaced links and the closed end 18 of the link 12 (Figs. 3 and 7) provides a pintle or cross bar which supports a lever member 20.

The lever 20 consists of a piece of sheet metal 15 one end of which is bent or rolled to form a socket or sleeve 21 which surrounds the pintle or pivot 18, and the other end is provided with a serrated edge 22 bent rearwardly at an angle to its body portion, as shown more clearly in Figs. 3, 5 and 6. 20 Between its ends the lever 20 is provided with integral lugs 25 and 26, each lug extending rearwardly substantially at a right angle to the body of the lever and then laterally, as shown more clearly in Figs. 5, 6 and 7. The lugs are so constructed and arranged that when the lever 20 is swung counterclockwise, as viewed in Fig. 5, from open or extended position to closed or nested position, as shown more clearly in Figs. 8 and 9, their laterally projecting portions engage the legs 30 14 and 15 of the link member and hold the lever 20 in such position that its outer surface is substantially flush with the outer edges of the link member.

When both the link and lever members are in 35 open or extended position (Figs. 5, 6 and 7), the entrance to the chamber 9 through the free end of the holder is wide open and the arrangement of the parts is such that the ends of the cord 1 may be quickly and easily inserted therein, even 40 though they are considerably frayed, it being noted that the legs of the link member do not in any way obstruct the opening, but on the other hand constitute, in effect, guiding members operative to direct the ends of the cord into the 45 chamber 9.

When the lever is swung counterclockwise (as viewed in Figs. 5 and 8) to closed position its body portion fills in or spans the gap between the legs of the link member and in swinging the lever to 50 closed position its free end forces the ends of the cord 1 into the chamber 9 as shown in Fig. 9. With the parts thus disposed, the lever and link members are firmly locked together and act as a unit, the serrated edge 22 being positioned to 55 engage the cord in the chamber so that when these members are swung counterclockwise from the position shown in Fig. 8 to nested position within the chamber, the serrated edge is simultaneously positioned so that its teeth are em- 60

bedded in the cord and firmly clamp the same against the inner surface of the top wall 5 of the holder. As the laterally projecting lugs 25, 26, engage the legs of the link member, the lever 5 is firmly locked in clamping position and can not be moved without swinging the link member from its nested position to an extended position.

It will be noted that in a clasp constructed in accordance with the present invention the ends 10 of the cord are firmly held within the body of the clasp and are substantially concealed, even though they may be considerably frayed. Moreover the parts are such that when closed their outer surfaces are substantially flush and present 15 the effect of a continuous unbroken surface, free from projections which might cause annoyance or discomfort to the wearer.

It will be noted that when the parts are disposed in clamping position (Figs. 1 to 4) the 20 outer surface of the lever 20 and the legs of the link 12 and the edge of the walls 6 and 7 are substantially flush, presenting in effect a smooth, continuous surface which constitutes the bottom wall of the holder, and as the ends of the cord 25 are clamped within the chamber 9 they are wholly enclosed by the top and side walls and the bottom wall defined by the lever 20. Even though the ends of the cord may be considerably frayed, they are completely concealed within the chamber 9, and hence do not detract from the attractive 30 appearance of the ensemble.

While I have shown and described one desirable embodiment of the invention it is to be understood that this disclosure is for the purpose 35 of illustration only and that various changes in shape, proportion and arrangement of parts, as well as the substitution of equivalent elements for those herein shown and described may be made without departing from the spirit and scope of 40 the invention as set forth in the appended claims.

I claim:

1. A clasp comprising a holder for receiving 45 a strand, a pair of spaced links pivoted to said holder and arranged to swing inwardly into a closed position upon said holder, and a lever pivotally secured to the outer ends of said links and arranged to swing into a closed position between said links, the free end of said lever having an 50 inwardly directed edge constructed and arranged to grip a strand disposed in said holder between the free end of said lever and said holder when said lever and links are swung into closed position.

2. A clasp comprising a holder having side walls 55 defining a chamber for the reception of a strand, a pair of links pivoted to said walls and arranged to swing inwardly into a closed position within said chamber, and a lever pivotally secured to the outer ends of said links and arranged to swing 60 into a closed position between said links, the free end of said lever having an inwardly directed edge constructed and arranged to grip a strand disposed in said chamber between the free end of said lever and said holder when said lever and 65 links are swung into closed position.

3. A clasp comprising a holder having side walls defining a chamber for the reception of a strand, a pair of links pivoted to said walls and arranged to swing inwardly into a closed position 70 within said chamber, a lever pivotally secured to the outer ends of said links and arranged to swing into a closed position between said links, a laterally projecting lug on said lever arranged to engage one of said links and hold said lever

in clamping position between said links, and an inwardly directed edge on the free end of said lever constructed and arranged to grip a strand disposed in said chamber between the free end of said lever and said holder when said lever 5 and links are swung into closed position.

4. A clasp comprising a holder having side walls defining a chamber for the reception of a strand, a pair of links pivoted to said walls and arranged to swing inwardly into a closed position within said chamber, a lever pivotally secured to the outer ends of said links and arranged to swing into a closed position between said links, said lever spanning the space between said links and constituting a closure wall of said chamber when said links and lever are swung into closed position, and means on the free end of said lever constructed and arranged to grip a strand disposed in said chamber between the free end of said lever and said holder when said lever 10 and links are swung into closed position.

5. A clasp comprising a holder having side walls defining a chamber for the reception of a strand, a pair of links pivoted to said walls and arranged to swing inwardly into a closed position within said chamber, a lever pivotally secured to the outer ends of said links and arranged to swing into a closed position between said links, said lever spanning the space 15 between said links and constituting a closure wall of said chamber when said links and lever are swung into closed position, a pair of laterally projecting lugs carried by said lever and arranged to engage said links to hold said lever in clamping position, and means on the free end of said lever 20 constructed and arranged to grip a strand disposed in said chamber between the free end of said lever and said holder when said lever and links are swung into closed position.

6. A clasp comprising a holder for receiving 40 a strand, a U-shaped link member having its legs pivotally secured to said holder and arranged to swing inwardly into a closed position upon said holder, and a lever pivotally secured to the closed end of said link member and arranged to swing into a closed position between the legs of said link member, the free end of said lever having an inwardly directed edge constructed and arranged to grip a strand disposed in said holder between the free end of said lever and said holder 45 when said lever and link member are swung into closed position.

7. A clasp comprising a holder having side walls defining a chamber for the reception of a strand, a U-shaped link member having its legs 55 pivotally secured to the walls of said holder and arranged to swing inwardly into a nested position within said chamber, a lever pivotally secured to the closed end of said link member and arranged to swing into a nested position between the legs 60 of said link member, said lever spanning the space between said legs and constituting a closure wall of said chamber when said link member and lever are swung into their nested positions, a pair of laterally projecting lugs carried by said 65 lever and arranged to engage the legs of said link member to hold said lever in clamping position, and means on the free end of said lever for gripping a strand disposed in said chamber between the free end of said lever and said holder 70 when said lever and link member are swung into nested position.

CHARLES A. DOMLER.
